(57) **CLAIM**

The ornamental design for a rechargeable fluorescent task lamp, as shown and described.

DESCRIPTION

FIG. 1 is a first perspective view of a rechargeable fluorescent task lamp;

FIG. 2 is a front, elevational view of FIG. 1;

FIG. 3 is a first side view of the rechargeable fluorescent task lamp of FIG. 1, which is a mirror image of the second side, and wherein the structures shown in broken lines form no part of the design;

FIG. 4 is a rear view of the rechargeable fluorescent task lamp of FIG. 1, wherein the structures shown in broken lines form no part of the design;

FIG. 5 is a top view of the rechargeable fluorescent task lamp of FIG. 1; and,

FIG. 6 is a bottom view the rechargeable fluorescent task lamp of FIG. 1.
